Primary Examiner — Ricky Pham(74) *Attorney, Agent, or Firm* — Muncy, Geissler, Olds & Lowe, P.C.(57) **CLAIM**

The ornamental design for a handle for kitchen knives, as shown and described.

DESCRIPTION

FIG. 1 is a front perspective view of a handle for kitchen knives showing my new design.

FIG. 2 is front elevation view of the handle for kitchen knives of FIG. 1.

FIG. 3 is a left side elevation view of the handle for kitchen knives of FIG. 1.

FIG. 4 is a top plan view of the handle for kitchen knives of FIG. 1.

FIG. 5 is a rear perspective view of the handle for kitchen knives of FIG. 1.

FIG. 6 is a right side elevation view of the handle for kitchen knives of FIG. 1.

FIG. 7 is rear elevation view of the handle for kitchen knives of FIG. 1; and,

FIG. 8 is a bottom plan view of the handle for kitchen knives of FIG. 1.

The broken lines in the drawings show environmental structure that forms no part of the claimed design.
